MULE SPINNING DEVICE

Robert A. Gard, Charlton City, Mass.

Application February 15, 1946, Serial No. 647,836

12 Claims. (CL. 57—45)

1

This invention relates to improvements in mule spinning machines and has particular reference to improved means and method of controlling the winding of the twisted yarn on the bobbins.

One of the principal objects of the invention is to provide novel means and method of controlling the winding of the yarn on the bobbins whereby the said yarn may be more tightly wound without danger of breakage.

Another object is to provide novel means and method of increasing tension on the yarn while it is being wound onto the bobbins and so controlling the introduction of said increased tension as to avoid directing breaking strain on the yarn during said winding.

Another object is to provide a device of the character described in the form of a separate attachment readily adaptable for use with conventional mule spinning machines.

Another object is to so relate the device with the operating mechanism of a mule spinning machine as to cause said device to operate only after the backing off operation.

Another object is to enable more yarn to be wound on the bobbin without any material increase in the diameter or resultant size of the filled bobbin.

Another object is to provide simple and efficient means for accomplishing the above results while decreasing the amount of doffing and changing of the bobbins during the spinning operation and thereby greatly increasing the output of the mule spinning.

Another object is to provide simple, efficient and economical means and method of controlling the winding of the yarn on the bobbins during mule spinning whereby the yarn on the resultant filled bobbin will be tightly wound, will permit a much greater amount of yarn to be wound on a single bobbin, will result in less tendency of the resultant yarn to slide on the bobbin, will permit much longer intervals of weaving without change of bobbin in the shuttle, will cause the windings of the yarn on the bobbins to have less tendency to become knotted during the weaving operation and therefore will greatly decrease the filling breakage, will result in less wastage of yarn due to the decreased requirement of bobbin replacement in the shuttle and the waste of yarn inherently lost with each change of bobbin and which in general will not only be a great time saver but will also decrease cost and greatly increase output both as to mule spinning and weaving.

Other objects and advantages of the invention will become apparent from the following descrip-

2

tion taken in connection with the accompanying drawings and it will be apparent that many changes may be made in the details of construction, arrangement of parts and methods shown and described without departing from the spirit of the invention as expressed in the accompanying claims. I, therefore, do not wish to be limited to the exact details of construction, arrangement of parts and steps of the method shown and described as the forms herein given are only by way of illustration.

Referring to the drawings:

Fig. I is a fragmentary diagrammatic perspective view showing the relation of the device of the present invention with the mule spinning machine;

Fig. II is a fragmentary view showing the relation which parts of the device assume during the operation of the mule spinning machine;

Fig. III is a fragmentary side elevational view of a modified form of the device embodying the invention;

Fig. IV is a front view of the device illustrated in Fig. III; and

Fig. V is a fragmentary side elevational view illustrating the raised and lowered positions of the guide and faller wires.

Prior to the present invention, the only means for introducing tension on the yarn during the winding operation of a mule spinning machine was the conventional weight arrangement. The gravitational pull of such weights which causes the tension faller wire to introduce tension on the twisted yarn during the backing off and winding operation of the machine is brought into play immediately when the reversed rotary movement is directed to the bobbins and just prior to the inward movement of the carriage.

Due to the above conventional arrangement, the amount of weight which it is possible to use without danger of causing the yarn to break during the backing off operation is limited to such an extent that the proper amount of tension cannot be directed to the twisted yarn during the winding operation with the result that, in the past, the yarn was very loosely wound on the bobbins. This not only allowed the yarn to slide on the bobbins and the windings to become snarled with each other during subsequent handling but also caused considerable knotting and breaking of the fillings during the weaving operation. Only a restricted amount of yarn could be wound on the bobbins and the operator was required to perform several doffing operations during a work day with a result that considerable

time was lost in removing the filled bobbins and replacing them during the spinning operation.

Such loosely wound bobbins also required frequent replacement of spent bobbins during the weaving operation and caused considerable loss of yarn due to wastage of the yarn remaining on each spent bobbin. The present invention overcomes all of the above difficulties in that it permits the twisted yarn to be more tightly wound on the bobbins during the spinning operation, greatly reduces the loss of time due to doffing, enables the yarn to be more easily spent from the bobbin during the weaving operation, requires less replacement of filled bobbins during the weaving operation and greatly reduces wastage due to the greatly reduced requirement of replacement of spent bobbins during the weaving.

Referring more particularly to the drawings wherein like characters of reference designate like parts throughout the several views, the invention relates more particularly to the provision of an attachment which may be readily applied to a conventional mule spinning machine embodying a carriage 1 having a plurality of spindles 2 thereon for supporting the bobbins 3. The spindles 2 are supported for rotation in the conventional manner. The carriage 1 is provided with wheels 4 which engage suitable guide rails 5 for longitudinal movement toward and away from supporting means 6 on which spools 7 are mounted. The spools 7 have the yarn 8 which is to be spun, wound thereon.

The yarn 8 is adapted to be drawn through suitable rollers 9 and 10 and the several strands of yarn are initially connected to the spindles 2 adjacent the heads of the bobbins. This is a conventional arrangement.

Suitable guide wires, such as the guide faller wire 11 and the tension faller wire 12, are provided for controlling the position of the windings of the strands of yarn 13 on the bobbins 3 and, also, for maintaining the desired tension on the strands during the winding.

The guide faller wire and the tension faller wire are carried by suitable hook-like supporting arms 14 and 15 respectively mounted on and secured to shafts 16 and 17. The said shafts are rotatably mounted in suitable bearings such as the bearings 18 and 19 carried by the respective supports 20 and 21 which are in turn secured to the carriage 1 as illustrated in Fig. I. The shaft 16, to which the arm 14 carrying the guide faller wire 11 is attached, and the shaft 17 to which the arm 15 carrying the tension faller wire is attached, are rotated to raise and lower the said guide and tension faller wires in the conventional manner and by conventional means not shown. The carriage 1 is moved forwardly and rearwardly by variable speed controls not shown and in the conventional manner. The tension applied to the tension faller wire 12, following the conventional practice is through the use of suitable weights 22.

The above-described mechanism is of the conventional type known in the art and for this reason various details of construction are not shown. A thorough description of the machine may be found in a publication on "High Speed Mules by Johnson & Bassett Incorporated, Worcester, Massachusetts" which description is of the machine to which the present invention is applied and the above is therefore part of the disclosure relied upon in this specification.

The attachment which embodies the essence of the present invention, as shown in Fig. I, com-

prises a lever 23 which is attached to the shaft 17 by a suitable set screw or the like 24. The lever 23 is provided with a pin 25 which is slidably supported in a slot 26 formed adjacent the upper end of the arm which is designated as a whole by the numeral 27. The said arm 27 is comprised of an upper portion 28 in which the slot 26 is formed and which is slidably mounted in a guide section 29. The lower end of the portion 28 is provided with a slot 30 through which a suitable bolt 31 carried by the guide section 29 extends for securing the upper portion 28 in adjusted position. The section 29 has a lower portion 32 rigidly secured thereto. The portion 32 is provided adjacent its lower end with a forwardly extending part 33 to which a latch roller 34 is pivotally connected.

The arm 27 has a lever 35 secured thereto by means of a bolt or the like 36. The lever 35 is provided with a projection 37 adjacent the forward end thereof to which one end of a coil spring or the like 38 is attached. The upper end of the coil spring 38 is detachably secured to a pin 39 carried by the lever 33. The tension of the spring 38 may be varied by loosening the bolt 36 and by raising or lowering the pin carrying end of the lever 35. The bolt 36 is then tightened to secure the lever in adjusted position. The upper portion 28 is adjustable relative to the guide section 29 to permit ease in the initial setting up of the device, and to enable the proper association thereof with the machine with which it is to be used. After having once been properly installed, no further adjustment is required. The lower portion 32 of the arm 27 lies within a guide slot 40 formed in the guide member 41 secured to the base of the carriage 1 by a suitable bolt or the like 42. A bracket 43 also secured to the base of the carriage 1 has a lever 44 pivotally secured thereto as at 45. The lever 44 is provided with a roller member 46 which is adjustably secured thereto by a pivot pin 47 adjustably mounted and capable of being locked in any desired adjusted position in a slot 48 formed in the adjacent end of the lever 44. The roller 46 engages a guide track 49 having a forward portion 50 secured to the floor by screws or the like 51. The portion 50 is joined with an inclined section 52 which in turn joins with a raised section 53 held in said raised position by any suitable means such as the block 54.

A spring 56 is secured to the lever 44 and to the forwardly extending portion 33 of the lower portion 32 to normally urge the roller 34 in a direction toward the adjacent end of the lever 44.

The function of the device is substantially as follows: In following the conventional practice, at the completion of each twisting operation the direction of rotation of the bobbins is reversed and the guide faller wire and the tension faller wire function to take up the slack in the yarn due to this reversed movement. This function results from the lowering of the guide faller wire and the raising of the tension faller wire from their positions such as shown in Fig. I to the positions diagrammatically illustrated in Fig. V. It is to be noted that the rotation of the shafts 16 and 17 to bring about this result causes the lever 23 to be lowered with the result that the arm 27 will simultaneously be moved in a downward direction in the slot 40. At the completion of the reversed movement of the bobbins, the carriage 1 starts to move inwardly along the guide rails 5. As the carriage moves inwardly, the latch roller 34 which is now moved an amount

sufficient to be positioned below the forward end of the lever 44 will move inwardly by the pull of coil spring 56 to a position beneath said end 44, as illustrated in Fig. II. As the carriage moves inwardly, the roller 46 will move upwardly of the inclined portion 52 and as it progresses further upwardly of the inclined portion will cause the lever 44 to rock on its pivot 45 and will cause the forward end thereof to depress the latch portion 34 and in this manner cause the arm 27 to be moved downwardly. This downward movement causes the tension on the spring 38 to be increased progressively as the roller 46 moves upwardly of the inclined portion 52 and is held at a given tension as the roller 46 moves rearwardly of the raised section 53. At a predetermined point along said raised section 53, there is provided an abutment member 55 adapted to engage the side surface of the latch member 34 and, as the carriage 1 progresses inwardly, cause said end to be pushed forwardly from beneath the lever 44 thereby relieving the increased tension directed to the coil spring 38.

The tension of the coil spring 38 through its connection with the lever 23 causes increased tension to be directed to the tension wire 12 and thereby causes the said tension wire to draw the strands 13 more tightly while the yarn is being wound onto the bobbin as the said carriage is moved in an inward direction.

The slot 26 in the upper end of the arm 27 is to permit the lever 23 to move in an upward direction when tension pull on the tension faller wire increases during the winding operation and this increased tension pull is resiliently resisted by the coil spring 38 and this function directs added tension on the yarn as it is being wound on the bobbins thereby resulting in a tighter wind.

It is particularly pointed out that the initial tension is directed to the tension faller wire through the releasing of the weights 22 in the conventional manner. The increased tension introduced by the coil spring 38 and its associated mechanism takes effect only after the backing off operation. This is due to the fact that the roller 46 is on the lower section 50 throughout the initial backing off operation and thence starts to direct increased tension on the spring 38 as the roller moves upwardly of the inclined portion 52 in proportion to said incline and as the carriage moves further inwardly and retains a given amount of tension on said spring 38 throughout the raised portion 53 until a point is reached wherein the abutment member will engage the latch end 34 and cause said end to become disengaged from beneath the lever 44 thereby relieving the tension pull on the spring 38. This increased tension pull causes the yarn to be held more taut as the carriage moves inwardly and during the interval throughout which the twisted yarn is being wound onto the bobbins. At the completion of this winding and as the carriage reaches a predetermined location inwardly, this tension is relieved and the tension faller wire and guide faller wire return to their normal function with the subsequent operations being in the conventional manner.

At the completion of this winding operation and when the bobbins are completely filled, the doffing operation is performed in the usual manner. Prior to doffing, the guide faller wire is manually operated in the conventional manner to produce a few windings of the yarn on the spindles below the base of the bobbins. At the

completion of this operation, the guide faller wire is down and out of the way but the tension faller wire is in a raised position. In order to doff, this tension faller wire must be lowered out of the way. This is accomplished, with the construction illustrated in Fig. I, by detaching the upper end of the tension spring 38 from the pin 39. This completely removes the function of the spring and permits the tension faller wire to be manually lowered and locked in this position in the conventional manner.

After the filled bobbins have been removed and fresh bobbins placed on the spindles, the tension faller wire and guide faller wire are moved to their operative positions simultaneous to rotary movement being imparted to the bobbins. This operation starts the unwindings at the base of the bobbins in the conventional manner. The upper end of the spring 38 is again latched with the pin 39 and the entire spinning operation is again repeated.

It is to be understood that the device embodying the invention functions every time the carriage is moved inwardly and throughout the complete winding operation and functions automatically throughout the spinning operation.

In Figs. III and IV there is illustrated a modified construction of arm 27' whereby instead of detaching the upper end of the tension spring 38 from the pin 39, as shown in Fig. I, the upper section of the arm 28', in this instance, is provided with a longitudinal slot 57 in which a plate 58 is slidably supported by the pivot bolts, pins or the like 59 and 60. The lever 23', in this instance, is pivotally connected to the plate 58 by the pivot bolt or the like 59 and is provided with an intermediate shouldered portion 64 which functions as stop means for limiting the inward movement of a lever 61 which is in turn pivotally connected, adjacent its lower end, to the plate 58 by the pivot bolt or the like 60. In this instance, the pin 62, simulating the pin 39 and to which the upper end of the coil spring 38' is attached, is carried by the lever 61. The upper portion 23' of the arm 27', in this instance, is provided with a stop member 63 which is adapted to limit the outward and downward swing of the lever 61, as shown by the dash lines in Fig. III.

With the above construction it will be seen that, when the lever 61 is in a raised position against the stop means 64, the tension pull of the coil spring 38' will be disposed on the side of the pivot 60 towards the stop means 64 and simultaneous to its function for increasing the tension on the tension faller wire will retain the lever 61 in said raised position. The tension pull of the coil spring 38', in order to doff, may be relieved by merely pulling the lever 61 forwardly and downwardly to a position illustrated by the dash lines in Fig. III.

At the completion of doffing and in order to bring the coil spring 38' again into play, all that is required is that the lever 61 be raised and pushed rearwardly to the position illustrated in full lines in Fig. III whereby the pull of the spring 38' will be directed to the lever 23' through the link plate 58 due to its free sliding movement longitudinally of the slot 57. The function of this device from here on is substantially the same as with the arrangement shown in Fig. I and described above.

From the foregoing description, it will be seen that simple, efficient, and economical means have been provided for accomplishing all the objects and advantages of the invention.

Having described my invention, I claim:

1. An attachment adapted to be associated with the supporting shaft of the tension faller wire and carriage of a mule spinning machine, said device comprising a lever attached to the tension faller wire shaft, an arm connected with said lever having a latch portion adjacent the lower end thereof, spring means connected with said lever and arm, a second lever pivotally connected with the carriage having its free end portion associated with the latch portion of the arm, said pivoted lever having a guide roller thereon, a guide rail on which the guide roller is adapted to be moved, said guide rail having a relatively low forward portion, an intermediate inclined portion and a raised rear portion and means associated with said guide rail for disengaging the latch member from the lever when the carriage is moved inwardly to a predetermined point.

2. An attachment adapted to be associated with the tension faller wire supporting shaft and carriage of a mule spinning machine, said device comprising a lever attached to the tension faller wire shaft, an arm connected with said lever having a latch portion adjacent the lower end thereof, a lever pivotally connected with the carriage having its free end portion associated with the latch portion of the arm, a guide rail, said pivoted lever having means adapted to follow said guide rail, said guide rail having a relatively low forward portion, an intermediate inclined portion and a raised rear portion, means associated with said guide rail adapted to be engaged by the latch member for disengaging said latch member with the lever when the carriage is moved inwardly to a predetermined point and spring means connected adjacent one of its ends to the lever attached to the tension faller wire shaft and adjacent its opposed end to the arm.

3. An attachment adapted to be associated with the supporting shaft of the tension faller wire and carriage of a mule spinning machine, said device comprising a lever attached to the tension faller wire shaft, an arm pivotally connected with said lever, spring means operably connecting said lever with said arm, a second lever pivotally connected with the carriage having its forward end associated with the arm, spring means for retaining said associated relation of said second lever and arm and means for moving said second lever on its pivot and for simultaneously moving the arm downwardly as the carriage moves inwardly.

4. An attachment adapted to be associated with the supporting shaft of the tension faller wire and carriage of a mule spinning machine, said device comprising a lever attached to the tension faller wire shaft, an arm pivotally connected with said lever, spring means operably connecting said lever with said arm, a second lever pivotally connected with the carriage having its forward end associated with the arm, spring means for retaining said associated relation of said second lever and arm, means for moving said second lever on its pivot and for simultaneously moving the arm downwardly as the carriage moves inwardly and means for disassociating said arm with the forward end of the second lever when the carriage is moved inwardly a predetermined amount.

5. An attachment adapted to be associated with the tension faller wire supporting shaft and a carriage of a mule spinning machine, said device comprising a lever attached to the tension faller wire shaft, an arm having a longitudinal slot adjacent the upper end thereof, means for operably con-

necting said slotted end with the lever, an adjustable member connected with said arm intermediate the ends thereof, resilient means operably connected with said adjustable member adjacent one end of said means and being operably associated with the lever adjacent its opposed end, said arm having a forwardly extending portion adjacent the lower end thereof, a second lever pivotally connected with the carriage and having the forward end associated with the rearwardly extending portion of the arm and means for moving said second lever a controlled amount as the carriage moves inwardly.

6. In a device of the character described for association with the supporting shaft of the tension faller wire and carriage of a mule spinning machine, said device comprising a lever secured to the supporting shaft, an arm having a longitudinal slot therein, means extending within said slot for pivotally and slidably connecting said lever with said arm, a member carried by said means extending within said slot having a pivot portion slidably supported in said slot, a second lever pivotally connected with said latter pivot and spring means connected with said second lever with said arm and being adapted to have its tension varied by movement of said second lever.

7. In a device of the character described for association with the supporting shaft of the tension faller wire and carriage of a mule spinning machine, said device comprising a lever secured to the supporting shaft, an arm having a longitudinal slot therein, means extending within said slot for pivotally and slidably connecting said lever with said arm, a member carried by said means extending within said slot having a pivot portion slidably supported in said slot, a second lever pivotally connected with said latter pivot and spring means connected with said second lever with said arm and being adapted to have its tension varied by movement of said second lever, said arm having a latch portion adjacent the lower end thereof, a third lever pivotally connected with the carriage and having a portion adapted to be engaged by said latch means of the arm and means for moving said third lever about its pivot controlled amounts as the carriage moves inwardly.

8. In a device of the character described for association with the supporting shaft of the tension faller wire and carriage of a mule spinning machine, said device comprising a lever secured to the supporting shaft, an arm embodying a portion having a longitudinal slot therein, means connected with said lever having a portion extending within the longitudinal slot for pivotally and slidably connecting said lever with said arm, said arm having a latch portion adjacent the lower end thereof, a second lever pivotally supported beneath the carriage having an end portion adapted to latch with said latch portion of the arm and spring means supported by said arm operatively associated with the means extending within and movable longitudinally of the slot and in turn functionally associated with the lever mounted on the supporting shaft adapted to have its tension varied by movement of the second lever beneath the carriage when said second lever is in latched relation with the latch portion of the arm.

9. In a device of the character described for association with the supporting shaft of the tension faller wire and carriage of a mule spinning machine, said device comprising a lever secured to the supporting shaft, an arm embodying a por-

tion having a longitudinal slot therein, means connected with said lever having a portion extending within the longitudinal slot for pivotally and slidably connecting said lever with said arm, said arm having a latch portion adjacent the lower end thereof, a second lever pivotally supported beneath the carriage having an end portion adapted to latch with said latch portion of the arm, spring means supported by said arm operatively associated with the means extending within and movable longitudinally of the slot and in turn functionally associated with the lever mounted on the supporting shaft adapted to have its tension varied by movement of the second lever beneath the carriage when said second lever is in latched relation with the latch portion of the arm and a second spring member in connected relation with the arm and adapted to normally urge the latch portion of said arm in a direction toward the end of the second lever member with which said portion is adapted to be latched.

10. In a device of the character described for association with the supporting shaft of the tension faller wire and carriage of a mule spinning machine, said device comprising a lever secured to the supporting shaft, a second lever pivotally supported beneath the carriage, an arm embodying at least two portions adjustable relative to each other in a direction longitudinally of said arm, one of said portions being pivotally connected with the lever carried by the supporting shaft and the other of said portions having a latch member adjacent the lower end thereof adapted to be latched with the adjacent end of the second lever and resilient means supported for resiliently biasing the longitudinal movement of one of said portions of the arm relative to the other and being adapted to have its tension varied by movement of the second lever when the end thereof is in latched relation with the latch member.

11. In a device of the character described for association with the supporting shaft of the tension faller wire and carriage of a mule spinning machine, said device comprising a lever secured to the supporting shaft, a second lever pivotally supported beneath the carriage, an arm embodying at least two portions adjustable relative to each other in a direction longitudinally of said

arm, one of said portions being pivotally connected with the lever carried by the supporting shaft and the other of said portions having a latch member adjacent the lower end thereof adapted to be latched with the adjacent end of the second lever, resilient means supported for resiliently biasing the longitudinal movement of one of said portions of the arm relative to the other and being adapted to have its tension varied by movement of the second lever when the end thereof is in latched relation with the latch member and means for progressively causing said second lever to be tilted a controlled amount about its pivotal connection as the carriage moves inwardly thereby causing the tension of said resilient means to be progressively varied in accordance with the tilting of the second lever.

12. In a device of the character described for association with the supporting shaft of the tension faller wire and carriage of a mule spinning machine, said device comprising a lever secured to the supporting shaft, a second lever pivotally supported beneath the carriage, an arm embodying at least two portions adjustable relative to each other in a direction longitudinally of said arm, one of said portions being pivotally connected with the lever carried by the supporting shaft and the other of said portions having a latch member adjacent the lower end thereof adapted to be latched with the adjacent end of the second lever, resilient means supported for resiliently biasing the longitudinal movement of one of said portions of the arm relative to the other and being adapted to have its tension varied by movement of the second lever when the end thereof is in latched relation with the latch member and means for normally urging the latch member toward the adjacent end of the second lever.
